UNITED STATES PATENT OFFICE.

JOSEPH H. MILLER, OF DULUTH, MINNESOTA.

CUSHION-HEEL AND MEANS FOR ATTACHING SAME.

1,092,378.

Specification of Letters Patent. Patented Apr. 7, 1914.

Application filed February 7, 1913. Serial No. 746,706.

To all whom it may concern:

Be it known that I, JOSEPH H. MILLER, a citizen of the United States, residing at Duluth, in the county of St. Louis and State of Minnesota, have invented certain new and useful Improvements in Cushion-Heels and Means for Attaching the Same; and I do hereby declare the following to be a full, clear, and exact description of the invention, such as will enable others skilled in the art to which it appertains to make and use the same.

My invention relates to cushion heels for boots or shoes and to means for attaching the same in such manner that, after the plates have been fixed to the base or body heel, the cushion heel may be positioned by the average wearer without the requirement of especial skill, or so removed and interchanged from one boot or shoe to the other or be replaced by new cushion heels.

It has for a further object the provision of a cushion heel and attaching plate so constructed and related as to provide a firm support, and so constructed as to discourage attempts to trim down the sides of a large size heel to make it fit a smaller body heel.

With these and other objects in view, it consists of the constructions, combinations and arrangements of parts hereinafter described and claimed.

In the accompanying drawings, Figure 1, is a top plan view of the attaching plate forming part of my said invention. Fig. 2 is a bottom plan view thereof. Fig. 3 is a rear end elevation thereof. Fig. 4, is a side elevation of the same. Fig. 5, is a top plan view of the cushion heel forming part of my said invention. Fig. 6, is a central vertical longitudinal section through said cushion heel and plate and through the body heel of a shoe. Fig. 7, is a perspective view partly in central vertical longitudinal section of a fragment of the body heel of a shoe and of my said invention.

In the drawings, 1, is an attaching plate having an upwardly directed peripheral knife-edge flange 1^a formed thereon. Formed upon said plate intermediate of its side edges are depending longitudinally directed vertical flanges 1^b. Intermediate of the center and rear end of said plate, there is formed thereon a depending transversely directed flange 1^c provided at its lower end with a rearwardly extending foot 1^d. Inter-

mediate of the center and forward end of said plate there is formed thereon a depending transversely directed flange 1^e provided at its lower end with a forwardly directed foot 1^f. In said cushion heel, 2, intermediate of its side edges are formed downwardly directed vertical recesses 2^a, adapted to receive and closely engage said flanges 1^b. In said cushion heel, intermediate of its center and rear end is formed a downwardly and rearwardly directed recess 2^c adapted to receive and closely engage said flange 1^e and foot 1^d. In said cushion heel intermediate of its center and forward end there is formed a downwardly and forwardly directed recess 2^d, adapted to receive and closely engage said flange 1^e and foot 1^f. Said flange 1^a is adapted to operate as a centering device and to conform concentrically and coextensively to the periphery of the body heel 75 of the shoe to which said plate is intended to be permanently secured. Upon adjusting said plate to the body heel, it may be tapped with a hammer so as to drive said flange into the body heel to mark the same 80 for trimming or to hold said plate in position while it is being screwed or nailed fast. Nail or screw holes 3, are formed in said plate near the periphery thereof for securing said plate to the permanent body heel 85 4 of the shoe. If desired, recesses 2^b may be formed in the upper face of the cushion heel to receive the nail-heads of nails directed through the holes 3.

It has heretofore been customary in many 90 cases for shoe repairers who were not temporarily provided with the desired sizes of detachable cushion heels to attach a large size plate and cushion heel, and to then trim down the sides of the cushion heel to conform to the contour of the body heel. It will be obvious in such case that if the plates on opposite shoes are not centered exactly alike on both body heels, that the trimming of one cushion heel to conform to the 100 body heel to which it is first attached will not adapt it to conform to the contour of the body heel of the opposite shoe so as to make the cushion heel satisfactorily interchangeable. When therefore the cushion heels 105 are afterward interchanged from one shoe to the other to equalize the wear, the consumer notes that the sides of the cushion heels are no longer flush with the sides of the body heel, and cannot be made so with- 110

out removal and skilled or tedious readjustment of the plates, wherefore he inclines to disapprove the whole idea of detachable interchangeable heels, and the market therefore becomes impaired. It is obvious that this fault cannot practically occur in the use of my invention, in which the area and contours of the plate and the sizes of the flanges and their distance from each other substantially fix the areas and contours of the body heel and cushion heel which may be secured together by it, and the plate on the body heel of one shoe being of the same size and style and flush with the sides of that body heel it follows that the cushion heel removed to it from the opposite shoe will fit exactly.

I am aware that it is not new to make an attaching plate "in the nature of an open frame" for attaching cushion heels to shoes, but it will be observed that my plate is not an open frame in the sense that the material feature of such open frames is that they are intended to remain in whole or in part unfilled, to provide an open space, or spaces, or open recesses between the bottom face of the body heel and the cushion heel, on the contrary it is one of the express features of my construction that the cushion heel is so molded as to provide elevations or raised portions X adapted to fill any openings in said frame and assist in providing a firm support; the temporary openings of my plate being merely incidental to an economical method of forming the flanges from a flat plate by means of dies as is well known in the art. Additional depending similar flanges may be formed on my said plate if desired, and said plate or cushion heel may

be altered or modified in minor details within the scope of certain of my claims.

What I claim is:

1. The combination with the body heel of a shoe, or boot, of a fastening plate coextensive in area with the bottom of said body heel, said fastening plate having formed thereon an upwardly directed peripheral knife-edge flange, said plate having formed thereon a depending transversely extending flange provided with a forwardly directed foot, said plate having formed thereon a depending transversely extending flange provided with a rearwardly directed foot, said plate having formed thereon a depending longitudinally extending flange, and a cushion heel of elastic material having formed therein recesses adapted to closely engage said depending flanges.

2. The combination of an attaching plate having an upwardly turned peripheral flange formed thereon, said plate having downwardly directed interior flanges formed thereon of material out of the horizontal area thereof, and a cushion heel having recesses formed therein adapted to receive said downwardly directed flanges, said cushion heel having raised portions formed thereon adapted to extend into the apertures formed in the horizontal area of said plate by the striking of material therefrom to form said downwardly directed flanges.

In testimony whereof, I hereunto affix my signature, in presence of two witnesses.

JOSEPH H. MILLER.
